A. Douglas.

Bustle.

No 17082

Patented Apr. 21, 1857.

UNITED STATES PATENT OFFICE.

ALEXANDER DOUGLAS, OF NEW YORK, N. Y.

BUSTLE.

Specification of Letters Patent No. 17,082, dated April 21, 1857.

To all whom it may concern:

Be it known that I, ALEXANDER DOUGLAS, of the city and county of New York, in the State of New York, have invented a new and Improved Bustle; and I do hereby declare that the following is a full and exact description thereof, reference being had to the accompanying drawings and to the letters of reference marked thereon.

10 Figure 1 is a plan and Fig. 2 a perspective view of my improved bustle as fitted to the person, Fig. 3 shows the same when not in use.

15 My invention consists of one or more strips of whalebone or other elastic material and one or more strips of cloth, corset lacing, or other flexible material, attached as represented, the latter being shorter than the whalebone. When in use the flexible 20 part adapts itself to the form of the wearer and the elastic strips stand out therefrom as represented in Figs. 1 and 2. My invention also includes the means represented of 25 making the magnitude of the bustle adjustable at pleasure by simply shortening or lengthening the flexible parts.

To enable others skilled in the art to make and use my invention I will proceed to describe its construction and use more in detail.

The same letters refer to like parts in all the drawings.

30 A, A, A, are strips of whalebone suitably attached to a cloth B which latter serves to steady, and hold them in their proper horizontal or nearly horizontal planes.

35 C C are strips of cloth, cord, or the like, which connect to A, A, at or near each extremity, and being somewhat shorter than A, A, compel the latter to stand in more curved form.

40 D, D, are strings, portions of cloth, or the like, by which the whole is bound upon the person. A, A, A, being elastic tend to assume a straight form; C, C, being flexible allow this to a considerable degree when the bustle is not in use but when placed upon the form the parts C C are bent to adapt themselves to the form and thus by diminishing the distance between their extremi-

ties compel a still more curved form in the longer parts A, A. Thus there always remains an empty space E between C and A and by this construction the dress is sustained in a fashionable position without adding materially to the weight or warmth of the clothing, a matter of considerable importance in warm weather.

I prefer to make this bustle a part of the skirt by using the upper portions of the latter to serve the purposes of B and D in the drawings, or in other words by sewing the parts, A, A, fast to the skirt in their proper positions, but I would not confine myself to such a use of the parts.

It may be desirable for obvious reasons sometimes to increase or diminish the size and effect of the bustle. I do this by providing eyelets or any of the ordinary means of forming what may serve as pulleys at or near each extremity of the strips A A and receiving through these the parts C C in the same manner as corset lacings are usually arranged in a corset. By drawing up or letting out the lacing when thus arranged the wearer can adjust the size of the bustle at pleasure. When the bustle is connected to, and forms a part of, the skirt the only effect produced on the front parts D D by tightening the lacing C is to somewhat extend the gathers on that part, but if the bustle is made independent the parts D D must of course either be made elastic or their lengths must be made adjustable by some of the ordinary means of taking in and letting out clothing, so that as the corset lacings C C are shortened D D may be lengthened and vice versa.

What I claim as my invention and desire to secure by Letters Patent is—

The combination of the elastic strips A, the steadyng cloth B (or its equivalent) provided with strips or fastenings D and the adjusting cord C substantially as described and the purpose specified.

ALEXANDER DOUGLAS.
